Intellectual Property Law(57) **CLAIM**

The ornamental design for an underarm garment shield insert, as shown and described.

DESCRIPTION

FIG. 1 is a front elevation view of an underarm garment shield insert showing our new design;

FIG. 2 is a rear elevation view thereof;

FIG. 3 is a right side elevation view thereof, the opposite side being a mirror image of the shown;

FIG. 4 is a top plan view thereof, the opposite side being a mirror image of the shown;

FIG. 5 is an isometric view thereof; and,

FIG. 6 is an in-use isometric view thereof.

The broken lines in FIGS. 1, 5 and 6 are environmental subject matter only and form no part of the claimed design.
